UNITED STATES PATENT OFFICE.

JOHN MIDDLETON RUTTER, OF GUILDFORD, ENGLAND.

RANGE OR STOVE.

Application filed August 31, 1921. Serial No. 497,410.

To all whom it may concern:

Be it known that I, JOHN MIDDLETON RUTTER, a subject of the King of Great Britain, residing at Inglenook, Aldershot 5 Road, Guildford, Surrey, England, have invented certain new and useful Improvements in Ranges or Stoves (for which I have applied for a patent in Great Britain, 165533, 30th March, 1921), of which the following 10 is a specification.

The object of the invention is to provide an improved domestic range or stove utilizing one fire for cooking, heating water for radiators and domestic use, and in one modification providing an open fire in a room adjoining that in which the cooking takes place.

According to this invention, a stove is constructed comprising a boiler extending 20 round three sides of the fire having perpendicular flue tubes passing through it and having above the said boiler an oven and hot plates so arranged that the hot gases after passing through the flue tubes of the 25 boiler, pass into the oven flues and heat the oven.

The invention will be thoroughly understood if reference is made to the accompanying drawings, in which:—

30 Figure 1 is a vertical section of a stove provided with boiler, oven flues, lifting grate, fire bars, ash box, and dampers in accordance with my invention.

Figure 2 is a section plan showing how 35 boiler surrounds the fire flues passing thru the boiler. The stove, oven hot plate flues and fittings and boiler may be made of wrought or cast iron or other suitable material.

40 Figure 3 is a detail perspective view of the boiler.

The fire front is formed of firebars attached to suitable framework, which may be surrounded by any form of finish or decoration 45 in the manner of ordinary fire places. The boiler is formed with one or more vertically disposed tubular flues of any suitable section. The hot gases may be made to pass by an arrangement of dampers down any or 50 all the tubes and pass under and upwards on the outer side of boiler on their passage to chimney.

The drawings, 1 and 2 show the tubes on one side of fire only, but others are made 55 with flue tubes on both sides of fire, where

more powerful boilers are required as diagrammatic view shown in Figure 3.

Boilers extending round three sides of the fire in a domestic range, and having vertical flue tubes through them are known, 60 and no claim to such boilers themselves is made.

The oven and hot plate are so arranged that they can be effectively utilized for cooking purposes at the same time as the hot gases 65 are being drawn through the boiler tubes to heat water, but the dampers are so arranged that the hot gases can be prevented from passing through boiler tubes when not required to do so.

70 The boilers represented in the drawing are open at the front and top.

Similar letters and numerals of reference throughout the illustrations indicate corresponding parts as follows:—

75 W^1 , W^2 , W^3 are water spaces, b are flue tubes passing through boiler from top to bottom round which the water circulates, b^1 are flues. The front bars a are removable. d is a main controlling damper in chimney flue. f is space above fire and boiler and under hot plate l . g is a swing damper to shut perpendicular boiler flue when horizontal, so that flame can proceed directly round oven. When this damper is turned up in a perpendicular position the flames and hot gases pass down boiler flue tubes before passing round outer side of oven O to chimney. l^1 is removable ring in hot plate. p is air space under front firebars and ashpit. r is the fixed frame-work with winder cog through which r^1 the vertical bar with teeth rises and falls. This bar is attached to fire grate and enables the fire to be raised or lowered at will. s are soot boxes or cleaning doors.

80 What I claim as my invention and desire to secure by Letters Patent of United States of America is:—

1. A stove comprising, in combination, a 100 boiler forming the back and two sides of a fire place, a plurality of flue tubes passing through the boiler, a hot plate over the fire place for deflecting the flames and hot gases from the fire place down the flue tubes of the boiler, another flue at the outer side of the boiler, communicating with the said flue tubes of the boiler, an oven above the boiler, a flue around the oven in connection with the side flue communicating with the flue 105 110

tubes of the boiler and means for supporting the boiler, the hot plate and the oven in their relative positions.

2. A stove comprising, in combination, a boiler forming the back and two sides of a fire place, a plurality of flue tubes passing through the boiler, a hot plate over the fire place for deflecting the flames and hot gases from the fire place down the flue tubes of the boiler, another flue at the outer side of the boiler, communicating with the said flue tubes of the boiler, an oven above the boiler,

a flue around the oven in connection with the side flues communicating with the flue tubes of the boiler, means for supporting the boiler, the hot plate and the oven in their relative positions and a damper arranged to direct the hot gases either down through the boiler tubes and subsequently up around the oven, or to direct said gases around the oven without passing through the boiler tubes.

In witness whereof I affix my signature.

JOHN MIDDLETON RUTTER.
